UNITED STATES PATENT OFFICE.

HIRSCH RAKOWITZKY, OF VILNA, RUSSIA.

MOUTHPIECE-ROLLING MACHINE.

1,072,259.

Specification of Letters Patent. Patented Sept. 2, 1913.

Application filed March 1, 1913. Serial No. 751,520.

To all whom it may concern:

Be it known that I, HIRSCH RAKOWITZKY, a subject of the Emperor of Russia, residing at 5 Połtawskaja, Vilna, in the Empire of 5 Russia, have invented a new and useful Mouthpiece-Rolling Machine, of which the following is a specification.

In known cigarette-making machines the mouthpieces for cigarette-wrappers were 10 hitherto rolled up in the manner, that the mouthpiece blank cut off from the continuous strip of mouthpiece forming material was introduced between a mandrel and a winding belt passing around the mandrel, 15 whereupon the blank was wound on the mandrel by means of the winding belt.

My invention relates to improvements in 20 such cigarette making machines, whereby the machine is simplified and the disadvantages connected with the winding belt are avoided.

The chief feature of the improvement resides in this that the winding belt is omitted and the continuous strip is itself utilized for winding the mouthpiece blank on the mandrel.

I will now proceed to describe my invention with reference to the accompanying drawing, in which—

Figure 1 is an elevation of the improved 30 rolling-up device, a table being shown in section, and Figs. 2 to 5 diagrammatically illustrate the various steps of the rolling-up of a mouthpiece. Fig. 6 is a detail plan view showing the relative positions of the 35 mandrel and rollers carrying the strip of material.

Similar characters of reference refer to similar parts throughout the several views.

On a table 39 two distinct frames 40, 41 40 are shown to be disposed. In the right frame 40 a mandrel 4, two small guiding rollers 2, 3, two large guiding rollers 5, 21 and a cam disk 32 are mounted to turn. The cam disk 32 is rigidly connected with a 45 gear wheel 25, which is driven from a main shaft 18 by means of a gear wheel 23 and an intermediate gear wheel 24. The gear wheel 25 meshes with a gear wheel 26, which is rigidly connected with the large lower 50 guiding roller 21. On a pin 42 provided in the right frame 40 a forked arm 28 is mounted to rock, which is rigidly connected with a lower arm 29 carrying a roller 30 adapted to roll on the periphery of the cam disk 32. 55 The forked arm 28 carries a pin 27, on which an upper guiding roller 22 is mounted to

turn. A pin 43 fastened on the lower end of the arm 29 is by means of a helical spring 31 elastically connected with a pin 44 fastened on the frame 40. The cam disk 32 is for the greatest part of its periphery circular and for the other part recessed at 45. The two arms 28, 29 are so set with regard to each other, that as long as under the pressure of the helical spring 31 the roller 30 rolls on the concentric portion of the cam disk 32 the guiding roller 22 supported by the forked arm 28 is held at a certain distance above the periphery of the lower guiding roller 21. When, however, the roller 30 engages in the recess 45 of the cam disk 32, the helical spring 31 will by means of the two arms 29, 28 press the upper guiding roller 22 against the lower guiding roller 21.

On the left frame 41 is fastened a pin 46 on which a lower pressing roller 8 and a two-armed lever 11 are mounted to turn independently of one another. The roller 8 is rigidly connected with a ratchet wheel 9, in which a pawl 10 provided on the upper arm 75 of the lever 11 is made to engage. On the main shaft 18 forming part of the cigarette-making machine (not shown) a grooved cam disk 15 is fastened and in its groove a roller 14 disposed on a lever 13 is made to engage. 80 The lever 13 rocks at 16 on a suitable bracket 17 beneath the table 39 and is pivotally connected by means of a link 12 with the lower arm of the above mentioned lever 11. By means of the roller 14 the lever 13 is set to 90 reciprocate from the main shaft 18, so that the pawl 10 feeds the ratchet wheel 9 from left to right during half a revolution of the main shaft 18, whereupon during the other half of the revolution the pawl 10 rides over 95 the backs of the teeth of the ratchet wheel 9, so that in this manner the lower pressing roller 8 is intermittently turned. Fastened on the frame 41 is a pin 47, on which a forked lever 49 is mounted to rock, which 100 by means of a pin 48 carries an upper pressing roller 6 and is by means of a helical spring 7 elastically connected with a pin 50 on the frame 41. A paper cutting-off device of any known construction is disposed 105 on the left frame 41, which device is here shown to consist of a stationary lower knife 19, a pin 51 fastened thereon, and a movable upper knife 20 rocking on the pin 51 and pressed against the stationary knife 19 110 by means of a helical spring 52 surrounding the pin 51. The movable knife 20 has a

lower slotted arm, in the slot of which a pin 36 at the upper arm of a two-armed lever 37 engages. The lever 37 rocks on a pin 38 provided beneath the table 39 and carries at its lower arm a roller 53, which engages in a groove of a grooved cam disk 54 fastened on the main shaft 18. It will be seen, that in this manner the movable knife 20 is caused to cut the paper once for every revolution of the main shaft 18.

10 The mandrel 4 may be either stationary or rotary. If a movable mandrel is employed it is rotated by frictional engagement with the movable strip 1.

15 The improved rolling-up device described operates as follows: An endless paper strip 1 is unwound from any roll (not shown) and passes around the lower guiding roller 2, the mandrel 4 and the upper guiding roller 3 in the manner clearly shown, then over the large guiding roller 5 and the upper pressing roller 6 and between the two pressing rollers 6, 8, over the lower stationary knife 19 and between the two guiding rollers 21, 22. The part of the strip 1 between the two pairs of rollers 6, 8 and 22, 21 is assumed to be horizontal and the mandrel 4 is so disposed, that this horizontal part forms a tangent to its lower side. The paper strip 1 is supported during its passage between the rolls 6, 8 and the spindle 4 by means of suitable tables, not shown in the accompanying drawings. The tension of the helical spring 7 is so adjusted 30 as to prevent the paper strip 1 from shifting between the two pressing rollers 6 and 8. The two frames 40, 41 are set at such a distance from each other, that a length of the paper strip 1 sufficient for the formation 35 of a mouthpiece can be cut off at the moment, that the right end of this blank just projects to the right from the vertical central plane of the two guiding rollers 21, 22, as is clearly shown in Fig. 5. The main 40 shaft 18 is made to run continuously, so that all the gear wheels 23, 24, 25, 26 and thereby the lower guiding roller 21 are made to constantly turn, while the paper strip 1 is on the contrary intermittently moved.

45 When a length of the paper strip 1 required for a mouthpiece moving from the cutting device 19, 20 (Fig. 5) projects to the right from the two guiding rollers 21, 22, it stops, whereupon the movable knife 20 is operated 50 for cutting off the blank. Immediately afterward by means of the roller 30 engaging in the recess 45 of the cam disk 32 the upper guiding roller 22 is pressed downward on the lower roller 21, so that the right end 55 of the paper strip 1 is gripped. Then the lever 13 moves from left to right so that the pawl 10 rides over the teeth of the ratchet wheel 9 and the paper strip 1 stops, see Fig. 2. At the same time the two guiding 60 rollers 21, 22 during their rotation in op-

posite directions move the blank toward the mandrel, so that its right end engages between the mandrel 4 and the paper strip 1. In one embodiment of the invention, the paper strip covers approximately three fourths or 270 degrees of the mantle surface of the mandrel. In feeding the strip between the mandrel 4 and web 1, the forward end of the strip or blank is so bent and guided that it will meet the web of material at an acute angle close to the point at which the cut blank or strip engages between the mandrel and said web. On a second and further rotation of the mandrel, the end of the cut strip will be so covered up by the material that the said strip is well wound upon the mandrel and it will therefore be unnecessary to further guide its winding movement. At the moment, that the right end of the blank is sufficiently gripped, the upper guiding roller 22 is by means of the roller 30 rolling on the concentric portion of the cam disk 32 again detached from the lower roller 21, so that the blank is released and is by means of the uncut paper strip 1 wound on the mandrel 4, see Fig. 3. Meanwhile the movable knife 20 had turned upward for permitting the paper strip 1 to move and the lever 13 had commenced its other stroke from right to left, so that the pawl 10 by means of the ratchet wheel 9 feeds the paper strip 1 forward, as is shown in Fig. 3. The right end of the moving paper strip 1 will engage the lower guiding roller 21 (Fig. 4), and when the blank has been wound on the mandrel 4, the right end of the paper strip 1 will project to the required distance from the two rollers 21, 22, whereupon the paper strip 1 stops and the cutting device 19, 20 is operated and immediately afterward the upper roller 22 is pressed downward for gripping the right end of the blank, as described above.

The rolled-up mouthpiece is in a known manner pushed from the mandrel 4 into a tube, over which the cigarette-wrapper is moved in order to be afterward taken off with the mouthpiece. This may be accomplished as follows: As soon as the cut blank 110 has been wound on the mandrel 4 so as to form a mouth piece, it is shifted from the mandrel and introduced into a cigarette wrapper by a thin cylindrical casing or tube sliding on and along the mandrel, and preferably having less thickness than the mouth piece formed by the rolled up blank or strip. To prevent a stoppage of this cylindrical casing by the web of paper, the axis of the guiding roller 6 may be so arranged 115 that it is not exactly parallel to that of the guiding roller 5, but positioned slightly out of alinement therewith. As the forward end of the cylindrical casing, during the rolling up of the cut blank or strip is in 120 125 130

contact with said strip, this forward end will be engaged by the web of paper, so that there is no danger of the forward border of the tube pushing against the border 5 of the web of paper. This action is preferably restrained by guides, supports, or the like (not shown) which coöperate with the mouth piece or with the cylindrical casing, and which may be operated in any suitable 10 manner.

The rolling-up device can be varied without departing from the spirit of my invention.

I claim:

15 1. The combination with a mandrel, of means for passing a paper strip around said mandrel, means for gripping the paper strip after leaving said mandrel and intermittently feeding it forward, means for 20 periodically cutting a mouthpiece-blank off the strip, and means for periodically gripping the cut blank and introducing its front end between said mandrel and the paper strip which is adapted to wind the blank on 25 said mandrel.

2. The combination with a mandrel, of a cutting device, means for passing a paper strip around said mandrel and between said cutting device, means for intermittently 30 feeding the paper strip, means for periodi-

cally operating said cutting device to cut a mouthpiece-blank off the strip, and means for periodically gripping the blank and introducing its front end between said mandrel and the paper strip which is adapted to 35 wind the blank on said mandrel.

3. The combination with a main shaft constantly turning, of a first grooved cam disk on said main shaft, a first pair of pressing rollers, a mandrel, means for passing a 40 paper strip around said mandrel and between said first pair of pressing rollers, means operated from said first grooved cam disk for intermittently rotating said first pair of pressing rollers forward, a cutting 45 device, a second grooved cam disk on said main shaft, means operated from said second grooved cam disk for operating said cutting device whereby a blank is cut off the strip, and means operated from said 50 main shaft for periodically gripping the cut blank and introducing its front end between said mandrel and the paper strip which is adapted to wind the blank on said mandrel.
